UNITED STATES PATENT OFFICE

170,576

AUTOMOBILE

Imogene H. Johnson, Tulsa, Okla.

Application March 12, 1953, Serial No. 24,003

Term of patent 14 years

(Cl. D14—3)

To all whom it may concern:

Be it known that I, Imogene H. Johnson, a citizen of the United States, residing at Tulsa, in the county of Tulsa and State of Oklahoma, have invented a new, original, and ornamental Design for an Automobile, of which the following is a specification, reference being had to the accompanying drawing, forming part thereof.

Figure 1 is a side elevational view of an automobile, showing my new design;

Figure 2 is a front view thereof;

Figure 3 is a rear view thereof, and

Figure 4 is a top plan view of the same.

I claim:

The ornamental design for an automobile, as shown.

IMOGENE H. JOHNSON.
